Primary Examiner — Patricia Palasik(74) *Attorney, Agent, or Firm* — Eckert Seamans Cherin & Mellott, LLC; Grant E. Coffield(57) **CLAIM**

The ornamental design for a vacuum port, as shown and described.

DESCRIPTION

FIG. 1 is a top isometric view of a vacuum port;
FIG. 2 is a bottom isometric view of the vacuum port of FIG. 1;

FIG. 3 is a top view of the vacuum port of FIG. 1;
FIG. 4 is a bottom view of the vacuum port of FIG. 1;
FIG. 5 is a right view of the vacuum port of FIG. 1;
FIG. 6 is a front view of the vacuum port of FIG. 1;
FIG. 7 is a back view of the vacuum port of FIG. 1; and,
FIG. 8 is a section view taken along line 8-8 of FIG. 6.
The portions shown in broken lines are for illustrative purposes only and do not form a part of the claimed design. The left side elevational views (not shown) of the vacuum port are mirror images of the right side elevational views.

1 Claim, 4 Drawing SheetsFIG. 7

FIG. 6
